MODULATION AND WOBBLING CHARACTERISTICS.

UNITED STATES PATENT OFFICE.

ELLISON S. PURINGTON, OF CAMBRIDGE, MASSACHUSETTS, ASSIGNOR TO JOHN HAYS HAMMOND, JR., OF GLOUCESTER, MASSACHUSETTS.

RADIANT SIGNALING SYSTEM.

Application filed April 27, 1922. Serial No. 556,971.

This invention relates to radiant signaling systems, and more particularly to such systems employing a plurality of frequencies.

Some of the objects of the present invention are to provide an improved signaling system; to provide an improved method of producing signaling currents for use in the transmission of intelligence; to provide a method of wobbling the frequency of the output current of a vacuum tube oscillator by varying the grid voltage and plate voltage at the desired rate of wobble in such a manner as to vary the frequency with substantially constant amplitude; to provide means whereby the frequency may be wobbled at a rate or frequency corresponding to the frequency of a current which flowing through a receiver will produce no audible sound; to provide a method of amplification for currents of radio frequencies such as are suitable for tone or speech transmission or for the transmission of other wave forms of frequency less than the fundamental radio, with an efficiency of power amplification substantially as great as obtained in the amplification of continuous or single frequency waves; to provide a system in which the reception of radiant waves may be made responsive to variations in frequency; and to provide other objects, which will appear hereinafter.

Referring to the drawings:

Figure 1 shows electrical connections of a transmitting system, in accordance with the present invention;

Figure 2 shows a receiving system;

Figure 3 shows a modified form of receiving system;

Figure 4 shows a modified form of transmitting system, and

Figure 5 shows curves of output current and of the wave length of the radiated wave with different grid and plate voltages of an oscillating tube.

Referring to Fig. 1, one embodiment of my invention comprises a vacuum tube 11 having a filament 12, grid 13, and plate 14. The filament is heated by a battery 15; and a suitable device such as a rheostat (not shown) may be provided in series with the battery 15 to regulate the filament current in a well known manner. Thus the negative terminal of the tube 11 becomes a hot cathode, and the electrons emitted therefrom pass to the plate 14, being controlled by the

potential of the grid 13 with respect to the hot cathode.

The circuit of the grid 13 includes a winding 20 of an inductive coupling 21, a grid battery 22, a potentiometer 23, and a connection to the hot cathode. Bridged around the potentiometer coils is a circuit including a blocking condenser 24, an adjustable resistance 25, and a source 26 of alternating current of the desired frequency of wobble, as will be more fully set forth subsequently. Thus there is provided a so-called resistance coupling between the source 26 and the circuit of the grid 13, but it is understood that any desired form of coupling, such as inductive or capacitative, may be employed, as will be readily understood by those skilled in the art.

The circuit of the plate 14 includes a winding 30 of the coil 21 shunted by a suitable condenser 34, a plate potential battery 31, conductor 32, and the middle or adjustable terminal of the potentiometer 23. A pair of by-pass condensers 33, 33 are bridged across the respective end portions of the winding of the potentiometer, being connected to each other and to the conductor 32. The voltage of the plate anode battery 31 is higher than that of either the grid battery 22 or the filament heating battery. Thus a regenerative or self-oscillatory circuit is provided, the pulsations in the circuit of the plate 14 being successively reproduced in the circuit of the grid 13 by the inductive coupling formed by the windings 20, 30 of the coil 21, the frequency being dependent upon the condenser 34 selected, and other factors.

The frequency of the oscillations of a tube regenerator of the type described depends among other things upon the values of the average or mean grid voltage and the average or mean plate voltage during a radio frequency cycle with respect to the hot cathode. With generator 26 not excited there will be a certain frequency produced in the oscillatory circuit 21, 34 depending among other things on the voltage of batteries 22 and 31. With generator 26 operating, alternating voltages are thrown into the grid and plate circuits of tube 11 superimposed upon the direct current voltages of the sources 22 and 31. The frequency is determined by the instantaneous voltages impressed on the grid and plate circuits respectively due to

the voltage sources 26, 22 and 31. The middle adjustable terminal or slider of the potentiometer 23 is provided to determine the relative voltages applied to said grid and plate circuits due to generator 26. By proper adjustment thereof and of rheostat 25, it is found that the generator 26 produces variations in the frequency of radio current in oscillatory circuit 21, 34, with substantially no variations in amplitude.

An output current produced by the regenerator is induced into a third winding 40 of the coil 21. This winding is included in the grid circuit of a high power amplifier 41 of conventional type having a filament heating battery 42 and a plate potential battery 43. A switch 51 controls the grid circuit of the amplifier. When used to produce current in the antenna circuit the switch 51 is closed, and voltages corresponding to the frequencies produced in the oscillatory circuit 30, 34 are impressed on the grid of amplifier tube 41. The plate circuit of the amplifier 41 includes a usual coil 45 whereby it is inductively coupled to the circuit of the antenna 46. It is understood that instead of transmitting the waves through the ether, the antenna and ground may be replaced by a pair of line wires for so-called wired wireless or guided wave operation. The electrical characteristics of the circuit of the antenna 46 should be such as to show no appreciable resonance effects in the range over which the frequency is wobbled.

In Fig. 5 there is illustrated graphically an example of voltage variations, and variations in amplitude and wave length obtained. The left hand portion of the figure shows the modulation characteristics of the system. The right hand portion shows the wobbling characteristics. If the voltages applied are periodically varied, the output current will be constant in amplitude while the wave length is wobbled as shown by the lines AOB respectively. In the particular case illustrated (in both figures) the grid voltage varies from -95 (at point A) with maximum opposition of the potential of source 26, to +20 (at point B) when the source 26 is aiding fully. The plate voltages are simultaneously varied between +160 and +210 respectively. The right hand portion of the diagram indicates that the wave length varies from 505 to 526 meters (i. e. frequencies of about 594,100 to 566,500). It is thus apparent that variations in frequency are produced, periodically without appreciable variation in amplitude.

The process of reception involves the production of modulated wobbled radio-frequency at the receiver, by having the radio receiver circuits tuned to one portion of the wobble frequencies, for example the high wave length end of the wobble. The received energy may then be detected in the

same manner as energy modulated at a secondary frequency equal to the frequency at which the transmitted energy is wobbled.

The electric waves produced by the transmitting station of Fig. 1 may be received by receiving systems similar to those shown in Figures 2 and 3. One form of receiving circuit is shown in Figure 2 for use with the rate of wobbling at frequencies within the range of audibility, or which can have their existence made known without the use of "beats".

For receiving and detecting the incoming energy there is provided a usual coupling 60 from the receiving antenna 61 and ground 62, or from a pair of line wires, a tuning condenser 63, and a detector comprising a three-element vacuum tube. The pulsations set up in the plate circuit of the tube 64 traverse one winding of a transformer 65 whereby the energy may be transmitted into the grid circuit of a usual three-element vacuum tube 66 for amplification. A by-pass condenser 67 of fixed capacity is provided in shunt with one winding of the transformer 65, and an adjustable condenser 68 is in shunt with the other winding thereof for tuning purposes. The condenser 68 may be used when the wobbling frequency is sine wave to tune to the output of the detector. For reception of speech, however, the variable condenser 68 may be set at zero capacity, it being understood that a suitable transformer 65, appropriate to speech frequencies is employed. The plate circuit of the tube 66 may be carried to an indicating device 69, which may take the form of a telephone receiver of conventional type, or the circuit may be carried through one or more additional amplifying devices in cascade. An adjustable condenser 70 may be provided for tuning the circuit of the receiving device if desired, but if such tuning is not desired, this condenser is preferably omitted.

For receiving electric waves wobbled at a rate corresponding to a supersonic frequency, a receiving circuit of the type shown in Figure 3 may be employed. In this circuit the same coupling 60, and tube 64 are used as in Figure 2. The right hand winding of the transformer 65 is connected in the circuit of the grid of a second detector tube 75, there being in this same circuit a secondary winding of a transformer 76 whose primary is in the circuit of a local source of electric oscillations such as a tube 77 connected for regeneration. The tube 77 has the usual filament connected with a filament heating battery 78. A transformer 79 is connected so that the oscillations in the plate circuit are reproduced in the circuit of the grid for continuous regeneration, the coil 79 providing an inductive coupling between the plate circuit and the grid circuit.

The plate circuit of the second tube 75 comprises an inductive coupling 80 whereby the oscillations in the plate circuit are induced into the grid circuit of an amplifying tube 81. The tube 81 is provided with three elements in a conventional manner, the filament being heated by a suitable battery 82 and the potential of the plate anode being maintained positive with reference to the 10 filament cathode by means of a suitable battery 82'. Included in the circuit of the plate of the tube 81 is a suitable indicating device 83 which may take the form of a usual telephone receiver or other desired indicating device.

A modified form of transmitting station is shown in Figure 4 in which a vacuum tube oscillator circuit 126 is substituted for the source 26, the connections otherwise being 20 the same as in Figure 1. Referring to Figure 4 more in detail, a three element vacuum tube 127 is provided, having its plate coupled back to the grid for regeneration by means of a coupling 128. Thus continuous 25 oscillations are produced, the arrangement of condensers and couplings being such as to set up oscillations of the desired frequency.

An inductive coupling 129 connects the plate circuit of the tube 127 with the circuit 30 of the potentiometer 23. Thus the potential across the outside terminals of the potentiometer 23 varies in accordance with the oscillations produced by the source 126 just described, the adjustment of the resistance 35 25 determining the effective voltage produced by the source 26 across the potentiometer terminals. Including in series with the secondary winding of the coupling 129 is a suitable blocking condenser 24. Thus an alternating voltage produced in the secondary winding of the coupling 129 is impressed 40 upon the outside terminals of the potentiometer 23, and the arrangement is such that the variations in potential thereby produced affects the grid and plate circuits of the tube 11 in such a manner that there will be substantially no variation in amplitude of the 45 output current of the tube 11, although variations in frequency occur, as previously described.

In operation, assuming a system employing the transmission station shown in Figure 1 and the receiving station shown in Figure 2, the source 26 and other power sources are 50 started, and the apparatus adjusted as described, and switch 51 is closed. The tube 11 operates as an oscillator of relatively high frequency, producing currents in oscillatory circuit 30, 34 which are varied in frequency 55 without change of amplitude. The cyclical rate of frequency variation, that is, the rate of occurrence of, for example, the peaks of highest frequency, is the same as the frequency of the current produced by the generator 26 and the extent of frequency varia-

tion is determined by the amount of voltage impressed by the generator upon the potentiometer 23. The rate of wobble may be, for example, 500 cycles per second, and the extent of wobble from a wave length of 505 to 70 526 meters, which would cause the mean value of the wave length to be 515.5 meters. Voltage corresponding to this current of wobbled frequency is impressed upon the grid of the amplifier tube 41 by means of the 75 coupling 21, and the output voltage of the amplifier tube is impressed in turn upon the antenna 46 by coupling 45. Because of the constancy of amplitude of voltages and currents of the tube 41, it may operate at much 80 higher electrical efficiency than if it were used to amplify currents which could be used to transmit tone by transmitter modulation rather than transmitter frequency variation. The nature of the current in antenna 46 may be checked by exploring with a wave meter with a thermal indicator. The presence of two symmetrical humps, one at about 505 meters and the other at about 526 85 indicate that the transmitter is in proper adjustment. Keying for signaling may be accomplished by opening and closing the switch 51. It may be otherwise accomplished by inserting the key in the lead from rheostat 25 to condenser 24, in which case 90 the current in antenna 46 is changed from continuous wave to wobbled wave.

The radiant energy is impressed upon the receiving antenna 61 and impressed from across the secondary condenser 63 into the 100 grid of the detecting tube 64 in the usual manner. The receiving circuits, however, are adjusted to sharp resonance, in contrast with the transmitting antenna circuit of Figure 1. The sharpness may be obtained 105 by use of receiving coils and condensers of sufficiently low decrement, or by use of regeneration in any of the well known manners. Thus a radio receiver is provided which responds only when the transmitter 110 wave is in the right portion of its cycle of wobble. For example, if the tuning is at 526 meters with the transmitter operating as above described, voltage will be impressed on the grid of the detector tube 64 once every cycle, constituting a voltage which is wobbled but also substantially completely modulated at a frequency of 500 cycles per second. If however the receiving circuit is 115 adjusted to be responsive at 515.5 meters, voltage will be impressed on the grid of the tube 64 twice every cycle of wobble, constituting a voltage which is wobbled at 500 cycles per second but substantially completely modulated at 1,000 cycles per second. By 120 the operation of the detector 64, currents are produced in the plate circuit corresponding to the amplitude variation of voltage upon the grid of the tube, and these are impressed 125 by coupling 65 upon the grid of tube 66, re-

peated in the plate circuit and indicated by device 69 in the usual manner.

For use as a radio telephone transmitter, the generator 26 may be replaced by a source 5 of speech voltage, such as the output of a microphone circuit comprising a microphone, battery and modulation transformer arranged in a well known manner. Or in case the power output of a microphone circuit is insufficient, a speech amplifier may 10 be used before impressing the voltage on the potentiometer 23. It is understood that for radio telephony all keys or switches shown in the diagram will be closed, the message 15 being sent by talking into the microphone. The rate of wobble and extent of wobble in this case correspond respectively to the pitches and intensity of the voice of the speaker. The receiving circuits are 20 appropriately tuned so that the modulation produced locally by resonance and impressed upon the grid of the detector will reproduce without production of marked overtones the voltage impressed on the potentiometer of 25 the transmitter.

The system comprising the transmitting station of Figure 4 and the receiving station of Figure 3 operates in a similar manner, the 30 operation of the oscillating tube 127 being obvious from the foregoing description. The receiving station of Figure 3 employs the beat system of reception, the tube 77 and inductive couplings 76-79 comprising a so-called heterodyne. The signals may be 35 transmitted by wobbling the frequency produced by the source 26 by varying the relative potentials of the grid and plate of the tube 127, in accordance with the message to be transmitted, and these signals produce 40 variations in the beats in the circuit of the tube 75.

It is obvious that the transmitting station shown in Figure 1 may be employed in combination with the receiving station of Figure 45 3, or with any other suitable form of receiving station, and similarly the transmitting station of Figure 4 may be employed in combination with the receiving station of Figure 2, or with any other suitable receiving 50 station.

It is well known that tuned circuits of the 55 general character of the circuits including the condensers 63-68 may be tuned in resonance with currents of predetermined frequencies. This implies that with a given value of electro-motive force impressed upon the circuit the intensity of the current varies according to the frequency of the current, being greatest at the frequency for which the 60 circuit has been designed to be in resonance and dropping off on each side of the predetermined frequency. The degree of intensity with deviations in frequencies from the selected one is extremely great at points immediately adjacent to the selected frequency 65

and the curve then rounds off and gradually forms a gently sloping line.

By resonance curve is meant a curve of current intensity, drawn to show variations in frequency, other factors being constant, such as shown in Fig. 207, page 294 of "Principles of Wireless Telegraphy" George W. Pierce. Referring to the right hand curve of this figure it will be seen that by sliding along the curve at its steepest portion between, for example 305 to 340 meters (between 373,000 and 357,000 cycles per second) there is a marked change in intensity of current. Slight changes or so-called wobbles in frequencies at the points where the slope of the curve is steepest produce greatly exaggerated changes in intensity or amplitude of current and the employment of this principle is one of the main features of the present invention. Thus by wobbling the 75 frequency produced by the tube 11 and employing tuned circuits, including condensers 63-68 which are resonant to frequencies closely approximating the frequency produced by the oscillating tube 11, great 80 changes in amplitude in the current in the indicating devices 69-83 are obtained.

The construction illustrated and described herein is merely what I now consider to be the preferred embodiment of my invention, 95 and it is therefore to be distinctly understood that I do not limit myself thereto as many changes may be made in points of detail and other embodiments resorted to without deviating from the true spirit and scope 100 of my invention as defined by the appended claims.

Having thus described the invention, what is claimed is:

1. The method of producing radiant oscillatory energy which comprises producing an oscillating current of substantially constant amplitude, automatically wobbling the frequency of said current, and utilizing said wobbled frequency current to produce radiant oscillations of substantially constant amplitude. 105

2. The method of producing radiant oscillatory energy which comprises producing in the plate circuit of a vacuum tube an oscillatory current of substantially constant amplitude, automatically wobbling the frequency of said current, utilizing said wobbled frequency current to produce radiant oscillations of substantially constant amplitude, and transmitting a message by modifying the condition of the current as being wobbled or unwobbled. 115

3. The method of producing radiant oscillatory energy which comprises producing in the plate circuit of a vacuum tube an oscillatory current of substantially constant amplitude, and wobbling the frequency of said current by varying proportionately the grid voltage and the plate voltage of the tube. 125 130

4. The method of producing radiant oscillatory energy which comprises producing in the plate circuit of a vacuum tube an oscillatory current of substantially constant amplitude, and wobbling the frequency of said current by periodically varying proportionately the grid voltage and the plate voltage of the tube. 10
5. The method of transmitting intelligence which comprises producing an oscillating current of substantially constant amplitude, wobbling the frequency of said current, impressing the oscillating current upon the ether, and receiving the radiant energy upon a circuit tuned slightly out of resonance with at least some of the frequencies employed, producing at the receiver current of a frequency bearing a definite relation to that at which the first-mentioned current is wobbled, and producing beats in the receiving circuit between said last-mentioned current and a local source of oscillations. 15 75 80
6. The method of transmitting intelligence which comprises producing in the plate circuit of a vacuum tube an oscillatory current of substantially constant amplitude, wobbling the frequency of said current, and transmitting a message by alternatively impressing the current upon the ether in wobbled and unwobbled condition. 85
7. The method of transmitting intelligence which comprises producing in the plate circuit of a vacuum tube an oscillatory current of substantially constant amplitude, wobbling the frequency of said current by varying proportionately the grid voltage and the plate voltage of the tube, impressing the oscillating current upon the ether, and receiving the radiant energy upon a circuit tuned slightly out of resonance with at least some of the frequencies employed. 90 95
8. The method of transmitting intelligence which comprises producing in the plate circuit of a vacuum tube an oscillatory current of substantially constant amplitude, wobbling the frequency of said current by periodically varying proportionately the grid voltage and the plate voltage of the tube, impressing the oscillating current upon the ether, and receiving the radiant energy upon a circuit tuned slightly out of resonance with at least some of the frequencies employed. 100 105
9. The method of transmitting intelligence which comprises producing an oscillating current of substantially constant amplitude, wobbling the frequency of said current, impressing the oscillating current upon the ether, receiving the radiant energy upon a circuit tuned slightly out of resonance with at least some of the frequencies employed, producing at the receiver current of frequency corresponding to that at which the first mentioned current is wobbled, and producing beats in the receiving circuit between said last-mentioned current and a local source of oscillations. 110 115 120 125 130
10. The method of transmitting intelligence which comprises producing in the plate circuit of a vacuum tube an oscillatory current of substantially constant amplitude, wobbling the frequency of said current, impressing the oscillating current upon the ether, receiving the radiant energy upon a circuit tuned slightly out of resonance with at least some of the frequencies employed producing at the receiver current of a frequency bearing a definite relation to that at which the first-mentioned current is wobbled, and producing beats in the receiving circuit between said last-mentioned current and a local source of oscillations. 10 75 80
11. The method of transmitting intelligence which comprises producing in the plate circuit of a vacuum tube an oscillatory current of substantially constant amplitude, wobbling the frequency of said current by varying proportionately the grid voltage and the plate voltage of the tube, impressing the oscillating current upon the ether, receiving the radiant energy upon a circuit tuned slightly out of resonance with at least some of the frequencies employed, and producing beats in the receiving circuit. 85
12. The method of transmitting intelligence which comprises producing in the plate circuit of a vacuum tube an oscillatory current of substantially constant amplitude, wobbling the frequency of said current by periodically varying proportionately the grid voltage and the plate voltage of the tube, impressing the oscillating current upon the ether, receiving the radiant energy upon a circuit tuned slightly out of resonance with at least some of the frequencies employed, and producing beats in the receiving circuit. 100
13. The method of transmitting intelligence which comprises producing in the plate circuit of a vacuum tube an oscillatory current of substantially constant amplitude, wobbling the frequency of said current by varying proportionately the grid voltage and the plate voltage of the tube, amplifying said current through a relatively high power tube, impressing the oscillating current upon the ether, and receiving the radiant energy. 110
14. The method of transmitting intelligence which comprises producing in the plate circuit of a vacuum tube an oscillatory current of substantially constant amplitude, wobbling the frequency of said current by varying proportionately the grid voltage and the plate voltage of the tube simultaneously, impressing the oscillating current upon the ether, and receiving the radiant energy upon a circuit tuned slightly out of resonance with at least some of the frequencies employed. 120
15. The method of transmitting intelligence which comprises producing in the

plate circuit of a vacuum tube an oscillatory current of substantially constant amplitude, wobbling the frequency of said current by periodically varying proportionately 5 the grid voltage and the plate voltage of the tube simultaneously, impressing the oscillating current upon the ether, and receiving the radiant energy upon a circuit tuned slightly out of resonance with at least some 10 of the frequencies employed.

16. The method of transmitting intelligence which comprises producing in the plate circuit of a vacuum tube an oscillating current of substantially constant amplitude, wobbling the frequency of said current by periodically varying proportionately the 15 grid voltage and the plate voltage of the tube simultaneously, amplifying said current through a relatively high power tube, 20 impressing the oscillating current upon the ether, receiving the radiant energy upon a circuit tuned slightly out of resonance with at least some of the frequencies employed, and producing beats in the receiving circuit.

25 17. In a transmitting system for radiant energy, means for producing oscillatory currents of constant amplitude, and means for varying the frequency of said currents, said last-mentioned means comprising a source of 30 alternating current.

18. A system of transmitting intelligence by radiant energy comprising means for producing an oscillating current of substantially constant amplitude, automatic means for 35 wobbling the frequency of said current, without substantially varying its amplitude, and means for utilizing said wobbled frequency current to produce radiant oscillations.

40 19. A system of transmitting intelligence by radiant energy comprising means for producing an oscillating current of substantially constant amplitude, and means for wobbling the frequency of said current between predetermined limits, said last-mentioned means comprising a source of alternating current.

20. A system for transmitting intelligence by radiant energy comprising a vacuum 50 tube having a grid and a plate circuit, means for producing in said plate circuit an oscillatory current of substantially constant amplitude and means arranged externally of the plate circuit for varying the frequency, said last-mentioned means comprising a source of electrical energy.

21. A system of transmitting intelligence by radiant energy comprising a vacuum tube having a grid and a plate circuit, means 60 for producing in said plate circuit an oscillatory current of substantially constant amplitude, electrically energized means directly connected with both of said circuits for wobbling the frequency of said current, without substantially varying its amplitude

and means for utilizing said wobbled frequency current to produce radiant oscillations.

22. A system of transmitting intelligence by radiant energy comprising a three-electrode vacuum tube, means operatively connected with a plurality of electrodes of said tube for causing the tube to emit an oscillating current of substantially constant amplitude and means for varying the frequency 75 of said current, said last-mentioned means comprising a source of alternating current.

23. A system of transmitting intelligence by radiant energy comprising means for producing an oscillating current of substantially constant amplitude and wobbling the frequency of said current, means for impressing electro-magnetic waves produced by said current upon the ether, and means for transmitting a message by alternatively causing 80 the transmitted waves to be wobbled and un-wobbled.

24. A system of transmitting intelligence by radiant energy comprising a three-electrode vacuum tube, means connected with 90 the electrodes of said tube for causing it to produce an oscillatory current of substantially constant amplitude, means for wobbling the frequency of said current, comprising a source of energy separate from 95 those for causing the tube to produce oscillations and means for alternatively rendering said last-mentioned source of energy operative and inoperative on said tube.

25. A system of transmitting intelligence by radiant energy comprising a vacuum tube having a grid and a plate, means included in the circuits of the grid and plate of said tube for producing therein an oscillatory current of substantially constant amplitude and for varying the frequency of said current by varying proportionately the grid voltage and the plate voltage of said tube, means for impressing electro-magnetic waves produced by said current upon the 100 ether, and means for receiving the radiant energy comprising a circuit tuned slightly 105 out of resonance with at least some of the frequencies employed.

26. A system of transmitting intelligence by radiant energy comprising a vacuum tube having a grid and a plate, means operatively connected with said grid and plate for producing an oscillating current of substantially constant amplitude and for varying the frequency of said current, means for amplifying said current comprising a three-electrode vacuum tube of relatively high power, means for impressing the electro-magnetic waves produced by said current upon the ether, and means for receiving the 110 radiant energy comprising a circuit tuned slightly out of resonance of at least some of the frequencies employed.

27. A system of transmitting intelligence 115 120 125 130

- by radiant energy comprising a three-electrode vacuum tube, means operatively connected with a plurality of the electrodes of said tube for causing the production of an oscillatory current of substantially constant amplitude and periodically varying frequency, a vacuum tube of relatively high power for amplifying said current, means for impressing the electro-magnetic waves produced by said amplified current upon the ether, and means for receiving radiant energy comprising a circuit tuned slightly out of resonance with at least some of the frequencies employed.
- 15 28. A system of transmitting intelligence by radiant energy comprising a three-electrode vacuum tube, means operatively connected with a plurality of electrodes of said tube for causing the production of an oscillatory current of substantially constant amplitude and periodically varying frequency, a vacuum tube of relatively high power for amplifying said current, means for impressing the electro-magnetic waves produced by said amplified current upon the ether, means for receiving radiant energy comprising a circuit tuned slightly out of resonance with at least some of the frequencies employed, and means for producing beats in the receiving circuit.
- 20 29. A system for producing oscillatory energy, comprising means for producing an oscillating current of substantially constant amplitude, automatic, periodically-acting means for wobbling the frequency of said current, means for transmitting oscillations derived from said current and also of substantially constant amplitude, and means for alternatively rendering said wobbling 35 means operative and inoperative to send a message.
- 25 30. A system for producing oscillatory energy, comprising means for producing in
- the plate circuit of a three-electrode vacuum tube an oscillatory current of substantially constant amplitude, means directly connected with both the plate and grid circuits of the tube for wobbling the frequency of said current, and means for transmitting oscillation derived from said current and also of substantially constant amplitude.
- 35 31. The method of producing oscillatory energy which comprises producing in the plate circuit of a vacuum tube an oscillatory current of substantially constant amplitude, and wobbling the frequency of said current by causing a source of alternating current to vary proportionately the grid voltage and the plate voltage of the tube.
- 40 32. The method of operating a three electrode thermionic oscillator comprising a circuit connecting two of the electrodes which consists of producing in said circuit an oscillatory current of constant amplitude, and wobbling the frequency by varying proportionately the voltage of two of the electrodes.
- 45 33. The method of producing radiant oscillatory energy which comprises producing in the plate circuit of a vacuum tube an oscillatory current, wobbling the frequency of said current while maintaining its amplitude constant by periodically varying proportionately the grid voltage and the plate voltage of the tube simultaneously.
- 50 34. The method of transmitting intelligence which comprises producing in the plate circuit of a vacuum tube an oscillatory current, wobbling the frequency of said current at a rate equivalent to the superaudible frequency while maintaining the amplitude of the current substantially constant.

In testimony whereof I hereunto affix my signature.

ELLISON S. PURINGTON.
